Victor J. Evans

ATTORNEY

UNITED STATES PATENT OFFICE

FRED FOX, OF STAUNTON, INDIANA

WELL STUFFING BOX

Application filed May 22, 1925. Serial No. 32,229.

This invention relates to improvements in stuffing boxes and contemplates the provision of a separable box which owing to its relative association may be readily and easily placed on pumps, engines and valves and the like without removing the shafts from their bearings in order to slide the usual and conventional form of stuffing box thereon.

Another object of the invention is the provision of interfitting joints upon this novel form of stuffing box and which are so relatively associated as will be rigidly held upon the shaft and held against accidental displacement and when so associated will be so rigidly secured as will function as an integral portion of the body upon which it is attached.

With the above and other objects in view, the invention further includes the following novel features and details of construction, to be hereinafter more fully described, illustrated in the accompanying drawings and pointed out in the appended claim.

In the drawings:—

Figure 1 is a vertical section taken through a body and showing the manner in which this packing gland is attached thereto.

Figure 2 is a vertical sectional view taken on line 2—2 of Figure 1.

Figure 3 is a top plan view of the upper portion of the packing gland when separated.

Figure 4 is a side elevation of the upper portions of the companion portions forming the packing gland.

Figure 5 is a section taken on line 5—5 of Figure 2.

Referring to the drawing in detail, wherein like characters of reference denote corresponding parts, the reference character 10 indicates a cylinder head and 11 a pump shaft 40 extending therethrough, the cylinder head 10 having a packing box 12 provided therein so that the packing 13 provided therein may be placed around the pump shaft. The usual stud pins or bolts 14 have been provided and 45 these carry securing nuts or other securing elements 15 upon the outer ends thereof in order that the packing gland, which will be hereinafter described, may be drawn tightly into place with respect to the cylinder head 50 10 and upon the pump shaft 11.

The packing gland is formed of two companion parts as indicated at 16 and 17 respectively, each having neck portions 18 and 19 extending centrally and upwardly therefrom. The lower ends of these necks 18 and 19 are fitted within arcuate shaped cutout portions provided centrally in the companion members 16 and 17 and include semi-circular longitudinally extending channel portions or bores therein when so assembled for the reception and housing of the pump shaft 11 therein. The companion member 16 includes a downwardly beveled dove-tail slot 20 therein, while the companion member 17 includes an oppositely inclined dove-tail 21 in order that these companion members 16 and 17 when arranged in their interfitting relation with respect to the dove-tail connection will be rigidly held together and prevent their displacement upon an outward thrust, owing to the relative association of these companion members 16 and 17 as clearly illustrated in Figure 5 of the drawing.

In order to so provide connecting means upon the upper ends of the necks 18 and 19, I provide slots 22 upon the opposite sides of the bore or channel of the neck 18 while the neck 19 has included upon its corresponding side a pair of downwardly extending dogs 23 which are arranged in spaced relation to the inner sides of the neck 19 and which are adapted to fit within the slots 22 provided in the upper end of the neck 18 when so associating the dove-tail 21 on the companion member 17 into the dove-tail slot 20 provided in the companion member 16 in order that the companion members 16 and 17 as well as the necks 18 and 19 carried thereby will be associated in one operation upon the pump shaft 11 and when so tightening up upon the fastening elements in the form of nuts 15 carried upon the outer ends of the studs or bolts and the like 14 will cause the outer ends of the necks 18 and 19 to engage the packing 13 arranged within the packing box 12 within a cylinder head 10 and around the pump shaft 11.

It will thus be noted from the foregoing description and accompanying drawing that this invention provides an exceedingly use-

ful and advantageous stuffing box which will undoubtedly prove of great value when used upon wells, engines, pumps and the like owing to its separable connection in order that 5 bearings and the like do not have to be removed from a shaft in order to associate this packing gland thereon.

The invention is susceptible of various changes in its form, proportions and minor 10 details of construction, and the right is herein reserved to make such changes as properly fall within the scope of the appended claim.

Having thus described my invention what is claimed is:

15 A separable stuffing box gland comprising companion interfitting members, one of the members being provided with a downwardly and inwardly beveled dove-tailed slot, a dove-tail oppositely beveled to that 20 of the slot lockingly engaged within the slot to rigidly hold the members together to prevent displacement incident to outward thrust terminally and relatively thereof, necks of semi-circular groove formation projected at 25 right-angles from the members and disposed in juxtaposition, one of the necks being provided with notches within one end thereof, and spaced lugs carried upon the companion neck being adapted for reception within the 30 notches when the members are joined.

In testimony whereof I affix my signature.

FRED FOX.
